PUSH-BUTTON LOCK

Basil Egor, Valley Stream, N. Y.

Application October 20, 1948, Serial No. 55,489

5 Claims. (Cl. 292—359)

1

This invention relates to new and useful improvements in locks, and has more particular reference to locks of the push button type. These locks are associated with knobs located on opposite sides of a door. When the push button is positioned inwards, one of the door knobs is locked against being turned so as to be incapable of operating the latch of the door. The other knob is capable of being turned because it is associated with a cam for moving the push button back to its out position.

Heretofore, locks of the push button type included a control cam connected with the push button and operated by cams connected with the control knob, the knob which may open the latch at all times. These locks also included cooperative keeper elements working between the push button and members connected with the door knob which is locked.

This invention particularly proposes improvements in the mechanism and cams operating between the push button and the door knobs. It is proposed to associate a control disc with the knob which may be turned for opening the lock. It is further proposed to associate a keeper disc with the knob which is locked at times. It is proposed to provide the push button with a certain enlargement formed in a certain way cooperative with cam and locking elements upon these discs. The advantage of the new construction resides in its simplicity by which the lock may be manufactured exceptionally cheap, and in the durable construction.

Another important feature of this invention resides in associating a spring with the control disc in a certain way by which the discs are normally urged and held in positions in which the push button is free to be pushed inwards.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is an elevational view of a push button lock constructed in accordance with this invention, certain parts being broken away to disclose interior parts, and said lock being illustrated associated with a schematic showing of door and latch.

Fig. 2 is an enlarged transverse sectional view taken on the line 2—2 of Fig. 1.

Fig. 3 is a fragmentary enlarged sectional view taken on the line 3—3 of Fig. 1.

Fig. 4 is a side elevational view of the control disc and its outer rod used in the push button lock.

2

Fig. 5 is an end view looking in the direction of the line 5—5 of Fig. 4.

Fig. 6 is a plan view of the push button and certain parts integral therewith, illustrated per se.

Fig. 7 is an end view looking in the direction of the line 7—7 of Fig. 6.

Fig. 8 is an elevational view of the keeper disc and its inner rod used in the push button lock.

Fig. 9 is an end view looking in the direction of the line 9—9 of Fig. 8.

The push button lock, in accordance with this invention, includes a hollow flange 10 for attachment on the face of a door 11, provided with a latch 12 having a bolt 13 which may be moved inwards and outwards by turning a square rod 14 passing through the door 11 and through the latch 12. The door 11, the latch 12, and its bolt 13 are illustrated in dot and dash lines upon the drawing as they form no part of this invention and are not sold with the push button lock described herein. The hollow flange 10 has an outer wall 15. A cover plate 16 is mounted across the inner face of the flange 10 and is held in position with screws 17.

A door knob 18 is turnably mounted through said outer wall 15. This door knob 18 will be named the control knob as it is the one which may always be turned for operating the latch 12. The door knob 18 has a reduced inner end 19 which engages through a central opening in the outer wall 15. A ring 20 is mounted upon the inner end 19 and engages against the inner face of the outer wall 15 for supporting the door knob 18 in its turnable position.

The rod 14 will now be named an inner rod because it is inwards of the outer wall 15. An outer rod 22 is non-rotatively and slidably mounted axially in the inner end of said control knob 18, and rotatively extends into the hollow of said flange 10. This outer rod 22 is square in cross section and engages a complementary opening formed in the knob 18 by which the rod is non-rotatively and slidably connected with the knob 18. The said outer rod 22 is provided at its inner end with a control disc 24 axially of the rod 22 and housed in said hollow flange 10, and engaging against the inner end of the door knob 18. The inner rod 14 is axially aligned and turnably connected with the outer rod 22 and extends through the cover plate 16. One of these rods, namely, the rod 14, is provided with an axial peg 25 which engages a complementary opening in the outer rod 22 by which these rods are turnably connected.

The inner rod 14 is provided with a keeper disc 26 axially of said inner rod 14 and housed in the hollow of the flange 10 and spaced from the control disc 24 by a shoulder 27. Said peg 25 is axially of said discs 24 and 26. The keeper disc 26

is provided with a keeper disc 26 axially of said inner rod 14 and housed in the hollow of the flange 10 and spaced from the control disc 24 by a shoulder 27. Said peg 25 is axially of said discs 24 and 26. The keeper disc 26

engages against the cover plate 16. Since the control disc 24 engages the inner end of the knob 18, and since the discs 24 and 26 are separated by the shoulder 27, they are held against longitudinal motion but they are free to be turned. A peg 28 projects from and is eccentric of the keeper disc 26 and engages in a short arcuate slot 29 formed in the control disc 24 in order that said discs 24 and 26 may be turned together, except for a slight amount of play produced by said short slot 29.

A push button 30 is slidably mounted eccentrically of and through said flange 10. The push button 30 is connected with an enlargement 31 which slidably engages in a complementary opening 32 formed in the flange 10, by which the push button 30 is slidably disposed parallel to the axes of the rods 14 and 22. This enlargement 31 is slightly shallower than the depth of the space between the outer wall 15 and the cover plate 16 and limits sliding of the push button 30 from an "out" position to an "in" position. In an "out" position the enlargement 31 engages the outer wall 15, and in an "in" position the enlargement 31 engages the cover plate 16.

The control disc 24 is formed with a peripheral cut 34 having cam shaped edges 35 complementary to any cooperative with a cam 36 formed on the enlargement 31. This cam 36 has inclined surfaces 37 adapted to mate with the inclined surfaces 35 in the "in" position of the push button 30. These surfaces 35 and 37 are so inclined that when the control disc 24 is turned, the surfaces 35 cam outwards against the surfaces 37 in order to move the push button 30 to its "out" position.

Said keeper disc 26 is formed with a keeper slot 39 cooperative with a projection 40 formed on the enlargement 31 for latching the keeper disc 26 from turning when said push button 30 is in its "in" position. Said enlargement 31 is also provided with a space 41 between said cam 36 and said projection 40 through which the control disc 24 may turn when said push button 30 is in its "out" position. Fig. 1 shows the push button 30 in its "out" position and it should be noted that the projection 40 is to the outside of the keeper slot 39 so that the keeper disc 26 is free to turn. In this position of the push button 30, the control disc 24 is free to pass through the space 41.

An expansion spring 45 is mounted along a pair of opposed grooves 46 and 47 formed along the periphery of said control disc 24 and the outer wall 15 of the hollow flange 10. More particularly, the groove 47 is formed along the control disc, while the groove 46 is formed along the inner face of the outer wall 15 of the flange 10. This spring 45 has its ends resting upon the ends of the grooves 46 and 47. More particularly, the spring 45 rests at the points 48 comprising the ends of the groove 46 and simultaneously rested upon the points 49 comprising the ends of the groove 47. The points 49 are enlarged to form shoulders for supporting the spring 45. These enlargements 49 may be clearly seen in Fig. 4. The spring 45 normally holds and urges the control disc 24 into a position in which its cam surface 35 is aligned with the cooperative cam 36 of said enlargement 31 in order that said push button 30 may be pushed inwards to its "in" position.

The inner rod 14 is associated with a door knob 50. This door knob 50 has a reduced end 51 passing through the wall 52 of a hollow flange 53 mounted on the door 11. The door knob 50 is turnably mounted on the wall 52 by a ring 54 which engages upon the end 51 and engages the

inner face of the wall 52. A cover plate 55 is mounted across the inner face of the flange 53 and is held in position with screws 56. The flanges 10 and 53 are formed with openings 57 for screws by which they may be attached to the door 11.

A stem 58 projects from the enlargement 31 and is aligned with an opening 59 formed in the door 11 and with another opening 60 formed in the flange 53. In an emergency the latch 12 may be opened on the knob side 50 of the door by engaging a small implement through the openings 60 and 59, and pushing the stem 58 to move the push button 30 to its "out" position.

The operation of the push button lock may be understood from the following:

With the parts in the positions illustrated in Fig. 1, the knobs 18 and 50 may be turned to operate the latch 12 to withdraw and extend its keeper 13. The push button lock may be locked from one side of the door, merely by pushing in the push button 30 to its "in" position. The "in" position is one in which the projection 40 engages the opening 39 of the keeper disc 26 and in which the cam 36 engages in the opening 34 of the control disc 24 so that the cam faces 35 and 37 engage each other. Now the knob 50 cannot be turned because the keeper disc 26 is held non-rotative by the projection 40 engaging the slot 39. However, the door knob 18 may be turned for opening the latch 12 because the control disc 24 may turn a slight distance in one direction or the other, relative to the keeper disc 26 which is held stationary, since there is slight play between the peg 28 and the ends of the arcuate slot 29. When the knob 18 is turned the control disc 24 is correspondingly turned and the cam surfaces 35 working against the cam surfaces 37 move the push button 30 to its "out" position. In the "out" position the projection 40 is moved clear of the opening 39. Simultaneously, the control disc 24 is aligned with the space 41 so that it may be turned. Now the knob 18 may turn a sufficient distance to operate the latch 12 to withdraw the bolt 13.

In an emergency the latch 12 may be opened from the knob side 50 by engaging an implement through the openings 60 and 59 and pushing the stem 58 to move the push button 30 to its "out" position.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a push button lock, a hollow flange, a control disc and a coaxial keeper disc turnably connected in spaced positions within said hollow flange, means for turning said control disc, and a push button slidably mounted eccentrically of and through said flange parallel to the axes of said discs and having an enlargement within said hollow flange, means for limiting sliding of said push button to an out and an in position, said control disc and said enlargement having cooperative cams normally engaging each other for moving said push button into its out position when said control disc is turned, said keeper disc having a slot and said enlargement having a cooperative projection engageable therein for

locking said keeper disc from turning when said push button is in its in position, and said enlargement having a space between its cam and its projection through which said control disc may turn when said push button is in its out position in order that said spaced discs are free to turn.

2. In a push button lock, a hollow flange, a control disc and a coaxial keeper disc turnably connected in spaced positions within said hollow flange, means for turning said control disc, and a push button slidably mounted eccentrically of and through said flange parallel to the axes of said discs and having an enlargement within said hollow flange, means for limiting sliding of said push button to an out and an in position, said control disc and said enlargement having cooperative cams normally engaging each other for moving said push button into its out position when said control disc is turned, said keeper disc having a slot and said enlargement having a cooperative projection engageable therein for locking said keeper disc from turning when said push button is in its in position, and said enlargement having a space between its cam and its projection through which said control disc may turn when said push button is in its out position in order that said spaced discs are free to turn, one of said discs having a shoulder engaging the other of said discs for holding them in said spaced positions.

3. In a push button lock, a hollow flange, a control disc and a coaxial keeper disc turnably connected in spaced positions within said hollow flange, means for turning said control disc, and a push button slidably mounted eccentrically of and through said flange parallel to the axes of said discs and having an enlargement within said hollow flange, means for limiting sliding of said push button to an out and an in position, said control disc and said enlargement having cooperative cams normally engaging each other for moving said push button into its out position when said control disc is turned, said keeper disc having a slot and said enlargement having a cooperative projection engageable therein for locking said keeper disc from turning when said push button is in its in position, and said enlargement having a space between its cam and its projection through which said control disc may turn when said push button is in its out position in order that said spaced discs are free to turn, one of said discs having a shoulder engaging the other of said discs for holding them in said spaced positions, and a peg axially of one of said discs engaging an opening axially of the other of said discs for supporting them in said turnably connected positions.

4. In a push button lock, a hollow flange, a control disc and a coaxial keeper disc turnably connected in spaced positions within said hollow flange, means for turning said control disc, and a push button slidably mounted eccentrically of and through said flange parallel to the axes of said discs and having an enlargement within said hollow flange, means for limiting sliding of said push button to an out and an in position, said control disc and said enlargement having cooperative cams normally engaging each other for moving said push button into its out position when said control disc is turned, said keeper disc having a slot and said enlargement having a cooperative projection engageable therein for locking said keeper disc from turning when said push button is in its in position, and said en-

largement having a space between its cam and its projection through which said control disc may turn when said push button is in its out position in order that said spaced discs are free to turn, and an expansion spring mounted along a pair of opposed arcuate grooves formed along the periphery of said control disc and the adjacent wall of said flange and resting against the ends of said grooves and normally holding and urging said control disc into a position in which its cam is aligned with the cooperative cam of said enlargement in order that said push button may be pushed inwards to its in position.

5. In a push button lock, a hollow flange for attachment upon the face of a door and having an outer wall, a cover plate mounted across the inner face of said flange, a door knob turnably mounted on and through said outer wall, an outer rod non-rotatively and slidably mounted axially in the inner end of said door knob and rotatively extending into said flange and provided at its inner end with a control disc axial of said rod and housed in said hollow flange, said control disc engaging the inner end of said door knob, an inner rod for extending through said door for operating a latch mounted on said door and for supporting a second door knob, said inner rod being axially aligned and turnably connected with said outer rod and turnably extending through said cover plate and provided with a keeper disc axially of said inner rod and housed in said hollow flange and spaced by a shoulder from said control disc and engaging against said cover plate, a peg eccentrically on one of said discs engaging a short slot in the other of said discs in order that said discs turn together except for slight play produced by said short slot, a push button slidably mounted eccentrically of and through said flange parallel to said rods and having an enlargement within the hollow of said flange engageable in an out position of said push button with the outer wall of said flange and in an in position of said push button with said cover plate, said control disc and said enlargement having cooperative cams normally engaging each other for moving said push button into its out position when said control disc is turned, said keeper disc having a slot and said enlargement having a cooperative projection engageable therein for locking said keeper disc from turning when said push button is in its in position, said enlargement having a space between its cam and its projection through which said control disc may turn when said push button is in its out position, and an expansion spring mounted along a pair of opposed grooves formed along the periphery of said control disc and said outer wall of the hollow flange and resting against the ends of said grooves and normally holding and urging said control disc into a position in which its cam is aligned with the cooperative cam of said enlargement in order that said push button may be pushed inwards to its in position.
